UNITED STATES PATENT OFFICE

138,923

DESIGN FOR A COMBINATION BABY
WALKER AND STROLLER

Samuel Branner, Chicago, Ill.

Application June 8, 1943, Serial No. 110,401

Term of patent 3½ years

(Cl. D14—14)

To all whom it may concern:

Be it known that I, Samuel Branner, a citizen of the United States, residing at Chicago, in the county of Cook and State of Illinois, have invented a new, original, and ornamental Design for a Combination Baby Walker and Stroller, of which the following is a specification, reference being had to the accompanying drawing, forming part thereof.

Fig. 1 is a side elevational view of a combination baby walker and stroller, showing my new design;

Fig. 2 is a top plan view;

Fig. 3 is a rear view; and

Fig. 4 is a frontal perspective view of the major portion of the design.

I claim:

The ornamental design for a combination baby walker and stroller, as shown.

SAMUEL BRANNER.
